UNITED STATES PATENT OFFICE.

ANTONINO BELLERÉ, OF BOSTON, MASSACHUSETTS, ASSIGNOR TO BELLERÉ AUTOMATIC TRAIN STOPPING MACHINERY CO., OF BOSTON, MASSACHUSETTS, A CORPORATION OF MASSACHUSETTS.

AUTOMATIC TRAIN-STOPPING APPARATUS.

1,120,263.

Specification of Letters Patent.

Patented Dec. 8, 1914.

Application filed March 14, 1913. Serial No. 754,299.

To all whom it may concern:

Be it known that I, ANTONINO BELLERÉ, residing at Boston, in the county of Suffolk and State of Massachusetts, have invented 5 new and useful Improvements in Automatic Train-Stopping Apparatus.

My invention pertains to mechanically operated train stopping devices.

The object of my invention is to provide 10 a simple and practical mechanical device which when in operation will automatically stop and arrest a train, without the intervention of the engineer, by acting upon the power and brake mechanism the same as the engineer would were he desirous of stopping the train viz—by first completely cutting off 15 the steam to the engine cylinders, by means of the throttle valve, and secondly by applying the air brakes gradually so as to prevent the sudden shock and jar that the train 20 would be subjected to were the brake to be put on full force.

Another object is to provide positive 25 means for railway men to use in emergency cases without relying on the engineer's seeing their signals—as is customary by waving a flag or other danger signal—which at best only communicates a warning to the engineer, which is only effective when the latter heeds it. My invention will stop the train whether the engineer wants to or not in such cases.

Still another object is to provide a mechanically constructed device which will 35 safeguard against collisions in this way;—a train stopping for any reason at an unusual spot for any length of time can prevent the following train from colliding with it by placing upon the track some distance away 40 from it the hereinafter described engaging hook which will stop the approaching train as soon as contact is made with said hook, thus avoiding the worst kind of accident.

Still another object is to provide positive 45 mechanical means for stopping a train from the tower-house operating the neighboring switches. The operator there noticing that the engineer is not obeying his signals can stop his train before it reaches the switch, 50 by throwing a lever, which sets the engaging hook in position to act upon the co-acting parts carried on the train when it reaches it.

With the above and other objects in view,

the invention consists of the novel features of construction and the combination and arrangement of parts hereinafter described and claimed and illustrated in the accompanying drawings.

Referring to the drawings: Figure 1 is an elevation of a locomotive moving in the direction of the arrow, showing the application of the invention to the same, about to engage with the engaging hook on the track. Fig. 2 is an elevation of the invention, shown fixed transversely to the bottom of the cab 65 in position for operation. Fig. 3 is a longitudinal section along line 3—3 in Fig. 5. Fig. 4 is a section on line 4—4 in Fig. 2, showing the locking dog on the locomotive engaging with the engaging hook on the track about to be pulled off. Fig. 5 is a plan view of the device under the cab on the locomotive. Fig. 6 is an elevation of the mechanism just after being operated. Fig. 7 is a plan view in the cab, taken on line 75 7—7 in Fig. 1, showing the throttle valve lever in a full open position and the air brake shut off, as would be the case in a moving train just prior to the engaging of the locomotive with the hook on the track. Fig. 8 is the same view as Fig. 7, but shows the throttle valve closed and the air brake full on, which would be the case after the engagement of the locomotive and the hook on the track had taken place. Fig. 9 is a 85 diagrammatic view looking into and under the cab in the direction of the arrow in Fig. 1, showing the relation of the mechanism in a moving train, just prior to the engagement of the locomotive and the hook on track. Fig. 10 is a diagrammatic longitudinal sectional view through the locomotive where the invention is applied, showing one of the many methods of supplying the turning means to the device. Fig. 11 is a 95 diagrammatic view of a walking-beam type of engaging hook, fixed between the tracks and operated mechanically from the tower-house;—the hook is shown in a non operating position, permitting the co-acting parts on the locomotive to pass over it without engaging. Fig. 12 is the same as Fig. 11, but showing the engaging hook on the track set in operating position, to engage with the co-acting parts carried on the locomotive to 105 stop the passing train.

Like numerals refer to like parts throughout the several views of the drawings.

In the drawings numeral 1, is a turning axle on the locomotive having fixed to it the driving pulley or wheel 2, driving the wheel 3, which is fixed to and turns the auxiliary shaft 4 by means of a resilient driving chain or some such other means 5. The shaft 4 is supported by the brackets 6 to the locomotive 7 and carries upon it the friction-cone 8, which is fixed to turn with said shaft 4,—the winding drum 9 which is forced on to the cone 8 when the apparatus is in operation,—the coiled spring 10 which holds the winding drum 9 off of the cone 8, when the apparatus is not in operation,—the snapping and locking collar 11 which forces the drum 9 on to the friction-cone 8 against the pressure of the spring 10 when the apparatus is in operation,—the expansion spring 12 which is held compressed by the locking dog 13 ready for operation, and the longitudinal locking bars 14 which hold the winding drum 9 from turning until it is forced off of the edges 15 when the apparatus is in operation.

Fastened to the winding drum 9 is the cord, wire-rope or other pliable means 16, which is wound around the drum 17 and fixed to the shaft 18 with a knurled or friction collar 19 engaged with a friction spring 20 which keeps the drum 17 from turning of its own accord. The shaft 18 goes up into the cab of the locomotive and has fixed upon it the gear 21 and the intermittent driving gear 22. The gear 21 engages with the gear 23 which has a series of the teeth cut away and which gear turns loose on the shaft 24. To the gear 23 is attached a drum 25, which when in operation winds the cord, wire-rope or other pliable means 26 upon it and in so doing acts upon the throttle valve lever 27 pulling the same into the cut off position, as shown in Fig. 8. The intermittent driving gear 22 acts upon the intermittent gear 28 which is fixed fast to the shaft 29 the said shaft being a continuation of the one the air brake lever 30 is attached to, which lever 30 has an angular travel between the stopping posts 31 and 32 on the air brake valve 33.

The engaging hook 34 with the projecting points 35 and 36 is set between the tracks of the train desired to stop with the spikes 37 straddling the sleeper 38 preferably as suggested in Fig. 4;—the idea being to give the engaging hook some purchase on the ground to enable it to resist any tendency of being dragged by the contact with the passing train.

34 is a walking-beam type of engaging hook pivoted at 39 and supported by a bracket 40, which is fixed to the sleeper 38, which hook is operated through a mechanical linkage from the tower-house 41 through

the manipulation of the tower-house lever 42, as shown in Figs. 11 and 12.

Having thus described the parts to the invention the mode of operation is as follows;—The engaging hook 34 being set in position for operation engages with the locking dog 13 on the passing train and snaps or pulls the dog off of its seat, thereby immediately permitting the compressed spring 12 to expand and exert its force toward pushing the winding drum 9 off of the edges 15 of the longitudinal locking bars 14 (Fig. 5) and forcing the drum 9 to engage with and clutch to the friction-cone 8 and turn with it, thus winding upon the drum 9 the cord 16 and unwinding the same from the drum 17, which being fixed to the shaft 18 turns the same and consequently sets the gear 21 to turning the gear 23, which has enough working teeth to wind the cord 26 sufficient to bring the throttle lever 27 back in a position to completely cut off the supply of steam to the engine cylinders and keep it there at the same time permitting the gear 21 to keep turning without acting on the gear 23 until the cord 16 has become unwound from the drum 17. The turning of the shaft 18 also simultaneously operates the air brake 33 through the driving gear 22 which engages with the intermittent gear 28 which gear is shown with two teeth covering the angle of travel of the air brake lever, it being understood that any number of teeth may be used, the more teeth used to the angle the more gradual the brake is put on, consequently negativing the sudden stopping of the train and jarring and shocking of same as would be the case in applying the brake full on. Each complete revolution of the gear 22 moves the brake lever the angular distance that one of the teeth of the gear 28 travels through, and when the lever 30 has reached the full on position as shown in Fig. 8 the gear 22 may keep on turning without having any effect on the intermittent gear 28, until the drum 17 has become unwound.

It may be noticed from Fig. 7 that as the engineer operates the brake lever 30 under the ordinary working of the locomotive that is when my device is not in use, he thereby turns the shaft 18 through the intermittent gear 28 engaging with the gear 22 thus also causing the gear 23 to move through a short angular distance, which when the cord 26 is left slack, as it is supposed to be, will have no effect on the throttle valve lever 27, also that the latter is free from any complications due to the application of my invention to it and in no way does it interfere with the working of the same by the engineer, under ordinary running.

It may also be noticed that when the drum 17 has become unwound and the engine is still in motion that the pull between the

drums 17 and 9 (Fig. 6) will overcome the friction on the cone 8 and slipping will take place between the cone 8 and the drum 9. The operation of the device having been completed the same is set into gear again and ready for operation by winding the drum 17, compressing the spring 12 and locking the same with the locking dog 13, setting the drum 9 back on to the locking bars 14 and setting the gear 23 back to engage with the gear 21 as is shown in Figs. 1 and 7.

From the foregoing description it may be observed that the invention provides an exceedingly inexpensive, simple and practical mechanical train controlling or stopping apparatus; that it may be installed on any of the present locomotives or railroads, and that it will be effective and reliable in operation.

While the preferred embodiment of the invention has been shown and described in detail, it will be understood that I do not wish to be limited to the construction set forth since various changes in the form, proportion and arrangement of parts and in the details of construction may be resorted to without departing from the spirit and scope of the invention.

Having thus described the invention, I claim:

1. In an automatic emergency train stopping device, the combination with a locomotive, its air brake valve and steam throttle lever, of an auxiliary rotatable shaft adapted to be driven from a turning axle of the locomotive; a compression member loosely mounted on said shaft; a locking-dog adapted to be disengaged from said compression member, when engaging with co-acting means set on the track for the purpose; a rotating clutch fixed to rotate with said auxiliary shaft; a winding drum, adapted to move horizontally on said auxiliary shaft to engage and rotate with said clutch when acted upon by said released compression member; a rotatable vertical driving shaft, extending upward into the cab of the locomotive and provided with a pinion and an intermittent driving gear; a spool fixed to rotate with said vertical driving shaft; a cord having one end secured to said winding drum and wound on said spool adapted to unwind from the same and become wound on said drum; a winding member rotatably mounted on a vertical stud and provided with an interrupted gear for engaging with said pinion and with a cord having one end secured to said winding member and the other end secured to said steam throttle lever for drawing the same to the "cut-off" position; an intermittent gear fixed to said air brake valve engaging with said intermittent driving gear and adapted to advance said valve intermittently to the "on" position; and supporting means for holding the said device in operating position, substantially as shown.
2. In a mechanism of the character described, the combination with a locomotive, its air brake valve and motive power controlling lever, of an auxiliary rotatable shaft adapted to be driven from a turning axle of the locomotive; a compression member normally held under compression and freely mounted on said shaft; a locking member, holding said compression member compressed, and adapted to be disengaged from same; a rotating clutch fixed to rotate with said auxiliary shaft; a winding member rotatably and slidably mounted on said auxiliary shaft and adapted to frictionally engage with said clutch; a vertical driving shaft extending upward into the cab of the locomotive provided with a pinion and an intermittent driving gear; a spool member fixed to turn with said driving shaft; a cord or rope wound on said spool member and connected with said winding member adapted to unwind from said spool member and become wound on said winding member; a second winding member provided with an interrupted gear for engaging with said pinion and a cord secured to said motive power controlling lever for drawing the same to the "off" position; an intermittent gear fixed to operate with the air brake valve and adapted to engage with said intermittent driving gear of the driving shaft for intermittently advancing said air brake valve to the "on" position; and supporting means for holding said mechanism in the operating position, substantially as described.
3. In a mechanism of the character described, the combination with a locomotive, its air brake operating valve and power controlling lever, of an auxiliary shaft adapted to be driven by a rotating axle of the locomotive; a clutching member fixed to rotate with said auxiliary shaft; a loose drum slidably mounted and carried on said shaft, adapted to frictionally engage with said clutching member on said shaft; a compressed spring carried on said shaft, adapted to expand and shift said slidably mounted loose drum; a locking mechanism adapted to engage with a co-acting member set on the track and permit the said compressed spring to expand and clutch said loose drum to turn with said shaft; a vertical driving shaft provided with a pinion and an intermittent driving gear at the upper end and a drum on the lower end; a cable wound on said drum on said vertical shaft with one end of the cable fixed to said loose drum; a winding member engaging with and operated by said pinion of said driving shaft; a flexible cord connected with said winding member and firmly secured to said

power controlling lever; an air brake operating valve extension spindle; an intermittent gear fixed to said extension spindle and adapted to engage and operate with said intermittent driving gear, provided on said driving shaft; and supporting means for holding said mechanism in operating position, substantially as described.

4. A train stopping apparatus applied to a locomotive, consisting of compression means normally held under compression; a locking member; a driving clutch; a turning member, adapted to engage with said driving clutch; an operating shaft adapted to rotate with said turning member; a winding

member engaging with said operating shaft; a winding cord secured to said winding member and connected with the power controlling lever, and adapted to shift the same to the "off" position; an intermittent turning means fixed to the air brake operating valve engaging with said operating shaft and adapted to intermittently advance said valve to the "on" position; and tripping means set between the tracks for engaging 29 with said locking member.

ANTONINO BELLERÉ.
